UNITED STATES PATENT OFFICE.

JULIAN KENNEDY, OF PITTSBURG, PENNSYLVANIA.

HOT-BLAST VALVE.

SPECIFICATION forming part of Letters Patent No. 760,873, dated May 24, 1904.

Application filed February 12, 1904. Serial No. 193,280. (No model.)

To all whom it may concern:

Be it known that I, JULIAN KENNEDY, of Pittsburgh, Allegheny county, Pennsylvania, have invented a new and useful Hot-Blast Valve, of which the following is a full, clear, and exact description, reference being had to the accompanying drawing, forming part of this specification, in which the figure is a side elevation, partly broken away, showing my improved valve and casing.

My invention relates to the class of hot-blast valves wherein the valve-seat is gripped between sections of the valve-casing, and more especially to the means for gripping and releasing the valve-seat. Heretofore these valve-seats have been drawn together to grip the seat, and to release the seats separate jacks have been used to jack up the upper part of the casing and release the seat, which was then drawn out and a new one inserted.

My invention is designed to do away with the use of separate jacks or means for forcing the gripping-rings apart and to provide mechanism for drawing the rings together, which may also be used for forcing them apart to release the valve-seat and take the weight of the upper part of the casing.

In the drawing, 2 represents the upper portion, and 3 the lower portion, of a hot-blast valve casing, these sections having their adjacent ends provided with rings 4, preferably of frusto-conical form, between which the valve-seat 5 is gripped. In the form shown 6 is the hot-blast main, and 7 the stove attachment, the passage being controlled by the water-cooled valve 8, which closes against the seat 5 and may be raised and lowered by the projecting stem 9.

To draw the gripping-rings 4 toward each other and grip the valve-seat, I provide the clamps 10, each consisting of screw-threaded stems with hook-shaped ends and an intermediate shoulder 11. The screw-threads of each pair of stems are engaged by a sleeve-nut 12,

having right and left hand threads engaging 45 the stems. The shoulders 11 of the clamp abut against the inner shoulders of the gripping-rings, while the hooks engage the upper and lower edges of these rings. By turning the sleeve-nuts in one direction the rings are drawn 50 toward each other to clamp the seat, while by turning the nuts in the opposite directions the casing-sections will be forced apart by the clamp-shoulders bearing upon them, thus jacking up the upper casing-section to release the 55 valve-seat, which may be drawn out and replaced.

The advantages of my invention result from the use of the surrounding row of clamps, which are also arranged to force the gripping-rings apart, thus doing away with the use of 60 separate jacks or apparatus for separating the casing-sections.

Variations may be made in the form and arrangement of the clamping-rings, the clamps, 65 the valve-seat, &c., without departing from my invention.

I claim—

1. A hot-blast-valve casing formed in two sections with clamping-rings at their adjacent 70 ends, a valve-seat between the rings, and clamps arranged to draw the rings together and having thereon means for forcing the rings and casing-sections apart to release the valve-seat; substantially as described. 75

2. In hot-blast-valve casing a pair of clamping-rings, hook-clamps arranged in pairs and engaging the rings, and nuts engaging the registering ends of the hook-stems, said hooks having shoulders arranged to engage and force 80 the rings apart; substantially as described.

In testimony whereof I have hereunto set my hand.

JULIAN KENNEDY.
